UNITED STATES PATENT OFFICE.

HOWARD W. ROBERTS, OF PHILADELPHIA, PENNSYLVANIA.

RUBBER-STAMP CABINET.

1,155,509.

Specification of Letters Patent.

Patented Oct. 5, 1915.

Application filed February 25, 1915. Serial No. 10,551.

To all whom it may concern:

Be it known that I, HOWARD W. ROBERTS, a citizen of the United States, residing at Philadelphia, in the county of Philadelphia and State of Pennsylvania, have invented 5 certain new and useful Improvements in Rubber-Stamp Cabinets, of which the following is a specification.

My invention relates to improvements in rubber stamp cabinets which are especially adapted for use in connection with an improved arrangement of rubber stamps supported in alphabetical order whereby the shipping department of any store or business house can know at a glance the condition of all accounts, and whereby a check is had upon bad accounts without the necessity of an inquiry at the credit department.

A further object is to provide an apparatus of the character stated in which a rubber stamp is provided for each customer, these stamps containing on the back the names and addresses and such other data as desired, and on the front or stamping surface, the 15 number and name of the customer, so that the bookkeeper in the credit department can instantly find the account by the number.

A further object is to provide an improved construction of cabinet having an 20 improved construction and arrangement of spacers, whereby the several rubber stamps may be supported and spaced apart, and which facilitates the removal and replacing of any stamp, and which arrangement of 25 parts permits any stamp to be withdrawn or others inserted without disarranging the other stamps in the cabinet.

With these and other objects in view the 30 invention consists in certain novel features 40 of construction and combinations and arrangements of parts as will be more fully hereinafter described and pointed out in the claims.

In the accompanying drawings: Figure 1 45 is a view in front elevation partly broken away illustrating a single cabinet or stamp support with its arrangement of spacers. Fig. 2 is a view in side elevation of Fig. 1 with a portion in section. Fig. 3 is a view 50 in transverse section on the line 3—3 of Fig. 2. Fig. 4 is a view of the front or operative face of one of the rubber stamps, and Fig. 5 is a perspective view of one of the spacers.

1 represents my improved cabinet. I use 55 this term "cabinet" in its broadest sense to include any receptacle in which the stamps

and spacers can be accommodated, and while it is my intention to utilize the cabinet in a vertical position, the invention is not limited in this respect.

The cabinet is preferably composed of metal having a back 2, sides 3, and ends 4. The front of the cabinet is open, and inwardly projecting curved flanges 5 are provided at the edges of the sides 3 to confine 60 the ends of my improved spacers 6.

Each spacer is composed of a strip of sheet metal having its ends 7 bent at an acute angle relative to the intermediate portion of the spacer, and the edges of said ends 70 7 are cut at an angle as shown at 8, so that the spacers assume an angular or inclined position relative to the back 2 of the cabinet. This inclination of the spacers compels the rubber stamps 9 to remain in the cabinet by 75 reason of gravity, as they tend to move inwardly and downwardly when once in the cabinet, and cannot accidentally fall out.

The ends 7, 7, of the spacers are bent inwardly at an acute angle as above stated, so 80 that the ends of one spacer bear against the upper or rear face of another spacer as shown clearly in Fig. 1, so that it is impossible to telescope one spacer upon another. The ends 7 of the spacers are of such a 85 length so as to properly accommodate between the spacers the rubber stamps 9 above referred to, and such spacers can be removed and replaced in the cabinet by positioning them at an angle to the longitudinal axis 90 of the cabinet as will be readily understood.

Each rubber stamp 9 comprises a block 10 which is preferably of wood or other similar light material having its sides 11 and ends 12 located at an angle so that the stamp will 95 find a ready entrance into its compartment, and there will be no loss of time in placing the stamp in the cabinet. It will also be noted that the rubber stamp is of a thickness slightly greater than the space between the 100 inwardly curved flanges 5 and the back 2 of the cabinet, so that it is impossible for the stamp to catch under or back of the flange, which would interfere with its quick release.

Each rubber stamp is provided with a finger hold 13, and on the back or outer face of the stamp, the name and address of the customer is found. This name and address may be placed upon the stamp by strips of 110 paper or other material, which can be readily removed and replaced, and of course, the

invention is not limited to this particular detail.

The inner or operative face of the stamp contains the customer's number and name, so that when the stamp is used on the package, the purchaser's account can be readily found because of the number.

In order that the shipping clerk might detect bad accounts, and not allow packages to go out of the store or business house, the rubber stamps can be either removed entirely and placed in another cabinet or a sticker of some kind can be placed on the outside or back of the rubber stamp so as not to interfere with the complete index of accounts.

With my improved apparatus, it will be noted that the shipping clerk has in front of him a complete index of all accounts, the names and addresses being on the back of the stamps, and it is to be understood of course, that the stamps will be arranged in alphabetical order in the cabinet, so that there will be no loss of time in securing any particular stamp. When a package goes to the shipping clerk, if the account is all right, he stamps the name and number on the outside. If the account is not all right, he holds up the package, and sends to the credit department the number of the account, so that it can be readily looked into.

I have not attempted to define the entire system in which my improved apparatus may be utilized, but simply defined a simple credit system which will indicate the usefulness of the apparatus, and save time at the shipping desk.

Various slight changes might be made in the general form and arrangement of parts described without departing from my invention, and hence I do not limit myself to the precise details set forth, but consider myself at liberty to make such changes and alterations as fairly fall within the spirit and scope of the appended claims.

Having thus described my invention, what I claim as new and desire to secure by Letters Patent is:

1. A rubber stamp cabinet having parallel sides and fixed flanges at the outer edges of said parallel sides projecting inwardly beyond the inner face of the sides, in combination with a plurality of spacers supported under the flanges and bearing against each other, substantially as described.

2. A rubber stamp cabinet having parallel sides and fixed flanges at the outer edges

of said parallel sides projecting inwardly beyond the inner face of the sides, in combination with a plurality of spacers supported under the flanges and bearing against each other, said spacers located parallel to each other and at an angle to the rear wall of the cabinet, substantially as described.

3. A cabinet of the character described having parallel sides and fixed flanges at the edges thereof projecting inwardly beyond the inner face of the sides, in combination with a plurality of removable spacers, each spacer having its ends bent at an angle and supported on the spacer below, substantially as described.

4. A cabinet of the character described having parallel sides and fixed flanges at the edges thereof projecting inwardly beyond the inner face of the sides, in combination with a plurality of removable spacers, each spacer having its ends bent at an angle and supported on the spacer below, the edges of said end portion located at an angle, whereby the spacers are located parallel to each other but at an angle to the rear wall of the cabinet, substantially as described.

5. A rubber stamp cabinet, comprising a back, sides, and ends, and fixed flanges at the front edges of the sides, projecting inwardly beyond the inner faces of the sides, a series of removable spacers in the cabinet, the ends of said spacers bent at an acute angle to the intermediate portions thereof and positioned under the said flanges, the ends of each spacer bearing against the adjacent spacer, substantially as described.

6. A rubber stamp cabinet, comprising a back, sides, and ends, and fixed flanges at the front edges of the sides projecting inwardly beyond the inner faces of the sides, a series of removable spacers in the cabinet, the ends of said spacers bent at an acute angle to the intermediate portions thereof and positioned under the said flanges, the ends of each spacer bearing against the adjacent spacer, and the said ends located at an angle whereby the spacers are disposed at an angle to the back of the cabinet, substantially as described.

In testimony whereof I have signed my name to this specification in the presence of two subscribing witnesses.

HOWARD W. ROBERTS.
